UNITED STATES PATENT OFFICE

CHARLES E. EBERSOL AND ROBERT GRIEVE, OF LANSING, MICHIGAN

CHECK-STUB HOLDER

Application filed August 16, 1928. Serial No. 300,130.

Because of the annoyance and trouble caused by the previously written check stubs while writing the next stub and check; and because the pad of checks easily drops from the check-pad holder when that holder is open, we have devised the following invention, which is a two-section gripping and slideable device for holding the pad of checks in the check-pad holder, and holding out of the way check stubs of pocket or folding check pads while writing the next check stub and check; and the objects of this invention are, first, to hold the pad of checks in the pad-holder; second, to hold out flat out of the way, all previously written check stubs, so that they will not interfere while writing the next check stub and check. This invention may be used in connection with other forms of books.

20 The invention is illustrated in the accompanying drawing in which Figure 1 is a side view of the entire device when open; Figure 2 is a plan view of the entire invention; Figure 3 is a detailed view of the entire invention in perspective; Figure 4 illustrates in perspective, details of the lower side of the grip and flat-tube of the stationary section; Figure 5 illustrates a side view of the slideable section; Figure 6 is a plan view of the slideable section which catches and holds back the check stubs, when it is pulled out; Figure 7 is a perspective view of the entire device in action.

That section illustrated by Figure 4 is pressed tightly upon the bound end of the pad of checks, with that portion in the form of a flat tube designated by 3, below the pad and the hook designated by 1 above it, after the pad of checks has been placed properly in the pad-holder—the spring tension of 1, holding the pad in the pad-holder and this section of the check-stub holder remaining stationary there until a new pad of checks is needed. Numbers 4-4 of Figure 4, shows the way in which the material is folded to form a flat tube in which the tongue 8, of the slideable section, Figure 6, easily is slideable. Figure 5 is a side view of that section which slides in the flat tube 3, Figure 4, to catch and hold all the previously written check stubs

back out of the way under 6 of Figure 5, leaving freedom for writing both the next stub and the next check.

By moving the slideable section of the assembled and complete invention as shown in Figure 2, slightly farther out, the previously written check stubs being held under 6, Figure 2, are immediately released for closing the check-book, and then as this same section is slid entirely into the flat tube of the stationary section attached to the book, 6 fits loosely over 1, allowing freedom in closing the check-pad holder.

In view, Figure 3, 10 represents a slot on the lower side along a portion of the flat tube to provide for the movable projection 9. That portion of Figure 3 designated by 5 provides a stop for the projection 9, to prevent pulling the slideable section entirely out of the flat tube, or farther out than is necessary to hold the stubs when they are turned back.

In Figure 7, 11 represents the check-pad holder with the Bristol board back, 15, of the pad of checks, 12, inserted in the pocket, 14, of the check-pad holder in such a way that the wide hook, 1 of the stationary section grips the bound end, 16, of the pad of checks to hold the pad in the check-pad holder. The written stubs, 13, in the pad are also represented by dotted lines, 17, as they are held out flat by the wide hook, 6, of the slideable section 8.

We claim:

1. A check-stub holder comprising a stationary section with a long straight portion in the form of a flat tube to be placed under the pad of checks, and with a wide hook on one end to grip firmly over the bound end of the pad of checks; and a slideable section, with a long straight portion which is slideable in and out of said tube just far enough for the wide hook on the outer end of the slideable section to catch and hold out flat, out of the way, all of the previously written check stubs while writing the next stub and check.

2. A check-stub holder comprising a stationary section with a long straight portion in the form of a flat tube to be placed under the pad of checks, and with a wide hook on one end to grip firmly over the bound

end of the pad of checks in such a way that the bound end of the pad of checks and the pocket portion of the check-pad holder are gripped together sufficiently tight to hold the pad of checks in the check-pad holder; and a 5
slidable section, with a long straight portion which is slidable in and out of said tube just far enough for the wide hook on the outer end of the slidable section to catch and hold out flat, out of the way, all of the previously 10
written check stubs while writing the next stub and check.
